UNITED STATES PATENT OFFICE.

MICHAEL A. CAPOBIANCO, OF GLEN COVE, NEW YORK.

SPARK-PLUG-CLEANING DEVICE.

Application filed October 15, 1923. Serial No. 668,692.

To all whom it may concern:

Be it known that I, MICHAEL A. CAPOBIANCO, a citizen of the United States, and a resident of Glen Cove, in the county of Nassau and State of New York, have invented 5 a new and Improved Spark-Plug-Cleaning Device, of which the following is a full, clear, and exact description.

This invention relates to a device for 10 cleaning spark plugs, and has for an object the provision of a simple, compact, efficient device which can be stored in the tool box of an automobile and is so constructed as to permit the ready cleaning of several sizes 15 of spark plugs with gasoline at any time it may be desired.

Another object is to provide a construction 20 which will permit a few accessories, such as extra spark plugs, cleaning sand- paper, and spark-gap cleaning blades, to be carried around in the device.

The invention is illustrated in the drawings, of which—

Figure 1 is a longitudinal section through 25 the device; and

Figure 2 is a section through a portion of 30 the device showing the manner in which a spark plug is attached thereto for the purpose of cleaning it with gasoline or other liquid.

The form of the invention shown in the drawings is a preferred form, although it is understood that modifications in the construction and arrangement of the parts and 35 in the character of the materials used may be adopted without departing from the spirit of the invention as set forth in the appended claims.

In order to provide a simple, compact device 40 which can be inserted in the tool box of an automobile to carry all the necessary apparatus for cleaning and washing spark plugs, I provide a container 1 having a cover plate 2 provided with a threaded bore 3 into which a threaded nipple 4 extends. This nipple is dependent from a collar 5. A washer 6 is disposed between the collar 5 and the cover 2.

The collar 5 is provided with a threaded 50 bore 7 into which a nipple 8 extends. This nipple 8 is dependent from a collar 9. A washer 10 lies between the collars 9 and 5.

The collar 9 is provided with a threaded bore 11 into which a nipple 12 extends. This 55 nipple depends from the bottom 13 of a container 15. A washer 14 lies between the

collar 9 and the bottom 13 of the container 15. The container 15 is of the same diameter as the container 1 and the collars 5 and 9, so that when fastened together in the manner shown they form one compact unit. The nipples 4 and 8 are hollow, whereas the nipple 12 is solid. The container 1 holds a can of gasoline or other cleansing fluid, whereas the container 15 is adapted to hold an extra spark plug 16, a spark-plug cleaning tool such as 17, and a few sheets of sand- or emery-paper, such as 18. The upper end of the container 15 is also provided with a readily removable cover 19 which, preferably, slidably engages the end of the container. It will be readily observed that the bores 3, 7 and 11 are of different diameters.

Figure 2 shows a spark plug screwed into 75 the bore 3 in the top of the container 1, and this plug bears against the washer 6 and can be shaken back and forth so that the cleaning fluid will thoroughly wash the spark plug, after which it can be scraped and the points thereof cleaned with the cleaning tool 80 17 or the sand- or emery-paper 18. If it is desired to clean a spark plug the threaded diameter of which is smaller than that shown in Fig. 2, then the collar 5 is allowed to remain in engagement with the container 85 1 and the collar 9 is unscrewed from the collar 5, exposing the bore 7, which is slightly smaller than the bore 3. If a still smaller bore is required, the container 15 is unscrewed from the collar 9 exposing the 90 bore 11.

In this manner, therefore, I have provided a simple, compact and efficient device which provides containers for cleaning fluid and the various appliances used in connection 95 with the cleaning and scraping of spark plugs, and these are ordinarily connected by interengaging collars and nipples each of which is provided with the proper sized bore to receive one or the other of standard makes 100 of spark plugs. This device is so compact, and when assembled is so tight, that it can be placed into a tool box without any likelihood of coming apart, so that the tools needed for this operation are kept together. 105

What I claim is:

1. A spark plug cleaning device which includes a container having a threaded bore, a collar having a dependent threaded nipple thereon adapted to be screwed into said bore, said collar in turn having a threaded bore of smaller diameter, and a second col- 110

- lar having a dependent nipple adapted to be threaded into the bore of the first-mentioned collar, said second collar having a threaded bore of still smaller diameter.
- 5 2. A spark plug cleaning device which includes a container having a threaded bore, a collar having a dependent threaded nipple thereon adapted to be screwed into said bore, said collar in turn having a threaded 10 bore of smaller diameter, a second collar having a dependent nipple adapted to be threaded into the bore of the first-mentioned collar, said second collar having a threaded bore of still smaller diameter, and 15 a second container having a dependent threaded nipple adapted to be threaded into the bore of the second-mentioned collar whereby the second container is held in engagement with said collars and the first- 20 mentioned container to form a single compact unit.
3. A spark plug cleaning device which includes a container having a threaded bore, a collar having a dependent threaded nipple 25 thereon adapted to be screwed into said bore, said collar in turn having a threaded bore of smaller diameter, a second collar having a dependent nipple adapted to be threaded into the bore of the first-mentioned collar, said second collar having a threaded bore of still smaller diameter, a second container having a dependent threaded nipple adapted to be threaded into the bore of the second-mentioned collar whereby the second container is held in engagement with 30 said collars and the first-mentioned container to form a single compact unit, and a plurality of washers disposed between the containers and the collars and between the collars themselves.
4. A spark plug cleaning device which includes a container having a threaded bore, a collar having a dependent threaded nipple thereon adapted to be screwed into said bore, said collar in turn having a threaded 35 bore of smaller diameter, a second collar having a dependent nipple adapted to be threaded into the bore of the first-mentioned collar, said second collar having a threaded bore of still smaller diameter, a second container having a dependent threaded nipple adapted to be threaded into the bore of the second-mentioned collar whereby the second container is held in engagement with 40 said collars and the first-mentioned container to form a single compact unit, and a plurality of washers disposed between the containers and the collars and between the collars themselves.
5. A spark plug cleaning device which includes a container having a threaded bore, a collar having a dependent threaded nipple thereon adapted to be screwed into said bore, said collar in turn having a threaded 45 bore of smaller diameter, a second collar having a dependent nipple adapted to be threaded into the bore of the first-mentioned collar, said second collar having a threaded bore of still smaller diameter, a second container having a dependent threaded nipple adapted to be threaded into the bore of the second-mentioned collar whereby the second container is held in engagement with 50 said collars and the first-mentioned container to form a single compact unit, and a plurality of washers disposed between the containers and the collars and between the collars themselves, said first-mentioned container adapted to hold a can of cleaning fluid, said second-mentioned container adapted to hold accessories such as extra spark plugs and spark plug cleaning devices.

MICHAEL A. CAPOBIANCO.
